UNITED STATES PATENT OFFICE.

JOSEPH F. BAKER, OF BARBERTON, OHIO.

CRUMB-TRAY.

1,095,490.

Specification of Letters Patent.

Patented May 5, 1914.

Application filed August 19, 1913. Serial No. 785,518.

To all whom it may concern:

Be it known that I, JOSEPH F. BAKER, a citizen of the United States, residing at Barberton, in the county of Summit, State 5 of Ohio, have invented certain new and useful Improvements in Crumb-Trays; and I do hereby declare the following to be a full, clear, and exact description of the invention, such as will enable others skilled in the art 10 to which it appertains to make and use the same.

This invention relates to crumb trays and has for an object to provide a device of this character having the leading edge rebent 15 upon itself to provide a resilient flange that facilitates the tray gliding smoothly over the surface of the floor or table while at the same time no sharp edges are produced to mutilate the carpet or table cloth.

20 A further object of the invention is to provide a yieldably mounted revoluble brush adapted to effectively sweep the crumbs into the tray.

With the above objects in view the invention 25 consists of certain novel details of construction and combination of parts herein-after fully described and claimed, it being understood that various modifications may be made in the minor details of construction 30 within the scope of the appended claims.

In the accompanying drawing illustrating this invention:—Figure 1 is a side elevation of a crumb tray embodying my improvements. Fig. 2 is a plan view. Fig. 3 is a 35 longitudinal sectional view on the line 3—3 Fig. 2. Fig. 4 is an underneath plan view of the tray.

Referring now to the drawing in which like characters of reference designate similar 40 parts, the tray is shown to comprise a bottom 10, side walls 11, and a rear wall 12, the leading edge of the bottom being rebent to present a flange 13 which extends at a slight angle to the bottom and is designed to bear 45 flat upon the carpet or table cloth from which it is desired to remove crumbs, the flange being resilient in character so that any desired pressure may be exerted upon the tray to promote the proper operation of 50 the tray under all conditions of service, said flange furthermore being curved at its juncture with the bottom of the tray whereby no sharp projections exist to mutilate the carpet or tablecloth while at the same time the smooth gliding of the tray is promoted.

A pair of forwardly projecting resilient arms 14 are secured to the leading edges of the sides 11 of the tray and journaled for rotation in these arms is a brush 15 that is equipped at one end with a rubber or similar 60 roller 16 that bears upon the carpet or table cloth and holds the brush at a uniform height therefrom, the resilient arms 14 yielding under pressure upon the tray to permit 65 of the roller functioning properly.

In operation the tray is advanced along the carpet or table cloth from which it is desired to remove crumbs, the brush being rotated by frictional engagement of the roller and bristles with the carpet or tablecloth, 70 and during such rotation of the brush the crumbs are brushed back into the tray.

From the above description it will be seen that I have provided an extremely simple and inexpensive crumb removing tray that 75 will be strong and durable, will effectively operate upon delicate fabrics without mutilating the same, and finally will be formed of a few parts that will not easily get out of order.

80 What is claimed, is:—

1. A crumb removing tray having the leading edge of the bottom rebent and producing a resilient supporting flange for the tray, in combination with resilient arms carried by the tray, a rotary brush carried by 85 said arms, and a gage roller carried by the brush to maintain the brush at a uniform height from the surface from which the crumbs are to be removed.

2. A crumb removing tray having the leading edge of the bottom rebent and producing a resilient flange that extends at a slight angle to said bottom, said flange being rounded at its juncture with said bottom 95 whereby no sharp edges exist and whereby the smooth gliding of the tray over the support from which the crumbs are to be removed is assured, and a rotary brush carried by said tray in advance of the leading 100 edge of the bottom and adapted to brush the crumbs into said tray.

In testimony whereof, I affix my signature, in the presence of two witnesses.

JOSEPH F. BAKER.
